PICTURE FRAME

Ernst J. Moeller, Long Island City, N. Y.

Application January 25, 1949, Serial No. 471

Term of patent 3½ years

(Cl. D29—20)

To all whom it may concern:

Be it known that I, Ernst J. Moeller, a citizen of the United States, residing at 31-07 21st Street, Long Island City, in the county of Queens and State of New York, have invented a new, original, and ornamental Design for a Picture Frame, of which the following is a specification, reference being had to the accompanying drawing constituting a part hereof:

Fig. 1 is a front perspective view of a picture frame showing my new design.

Fig. 2 is a side elevational view, the other side being the same.

Fig. 3 is a top view.

I claim:

The ornamental design for a picture frame, substantially as shown.

ERNST J. MOELLER.
